US0D1032689S

(12) **United States Design Patent** (10) Patent No.: **US D1,032,689 S**
(45) Date of Patent: ** Jun. 25, 2024

(54) **CAMCORDER**

(71) Applicant: **NingBo New Beam Digital Electronic Technology CO., LTD**, Zhejiang (CN)

(72) Inventor: **Shuqin Luo**, Zhejiang (CN)

(73) Assignee: **NingBo New Beam Digital Electronic Technology CO., LTD**, Ningbo (CN)

(**) Term: **15 Years**

(21) Appl. No.: **29/937,304**

(22) Filed: **Apr. 14, 2024**

(51) LOC (14) Cl. **16-01**

(52) U.S. Cl.

USPC **D16/202**

(57) **CLAIM**

The ornamental design for a camcorder, as shown and described.

DESCRIPTION

FIG. 1 is a front, top, and left perspective view of a camcorder showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a rear, bottom, and right perspective view thereof.

The broken lines shown in the drawings represent portions of the camcorder that form no part of the claimed design.
